UNITED STATES PATENT OFFICE.

ARTHUR P. PAYNE, OF NEW HAVEN, CONNECTICUT, ASSIGNOR TO WINCHESTER REPEATING ARMS COMPANY, OF NEW HAVEN, CONNECTICUT, A CORPORATION OF CONNECTICUT.

BATTERY HAND-LAMP SWITCH.

Application filed January 25, 1921. Serial No. 439,772.

To all whom it may concern:

Be it known that I, ARTHUR P. PAYNE, a citizen of the United States, residing at New Haven, in the county of New Haven, 5 State of Connecticut, have invented certain new and useful Improvements in Battery Hand-Lamp Switches; and I do hereby declare the following to be a full, clear, and exact description of the invention, such as 10 will enable others skilled in the art to which it appertains to make and use the same.

The present invention relates to portable electric lamps comprising a casing, a battery, and an incandescent lamp mounted 15 therein, and a contact device on the casing by which the flow of current from the battery through the lamp may be controlled at will.

In a portable lamp of this character, it is 20 desirable that the user shall be able to flash the lamp, that is, light it for short periods of time, as in signaling, or for such length of time as it is convenient for the operator to hold his thumb on the contact device. It 25 is also desirable that means be provided for closing the switch to light the lamp for a longer period of time and without the need for continuous thumb pressure on the contact mechanism.

30 It is an object of the present invention to provide a hand lamp with a contact mechanism so constructed that the lamp can be flashed by thumb pressure on a push button, or can be permanently lighted by a sliding 35 movement of said push button and its associated parts, but with the additional feature that there is a third position for the push button at which it cannot be depressed to light the lamp and from which the push 40 button is not likely to be accidentally displaced by a sliding movement, as when the hand lamp is carried about with tools or in the pocket of the user. In its preferred embodiment, the switch mechanism is 45 simple in design, is easy to assemble, is reliable in operation, does not project unduly, and possesses other advantages which will become clear from the following detailed description taken in conjunction with the 50 accompanying drawings, wherein—

Fig. 1 is a sectional elevation of a hand lamp constructed in accordance with the present invention; Fig. 2 is an enlarged elevation of the switch mechanism; Fig. 3 is a

section on the line 3—3 of Fig. 2; Figs. 4 55 and 5 are sections similar to Fig. 3 but with the push button in other positions; Fig. 6 is a transverse section on the line 6—6 of Fig. 2; Fig. 7 shows the stationary or inner contact finger of the switch with the 60 escutcheon plate and housing removed; and Fig. 8 is a detail of the push button housing.

In the embodiment illustrated, a battery case 1 of fiber or other suitable insulating material is provided at its bottom with a 65 threaded ring 2, on which is mounted a bottom cap 3 of metal carrying a coil spring 4 which engages the naked bottom of the lowermost dry cell 5. The uppermost dry cell 6 has its inner or carbon electrode 7 in 70 contact with the inner terminal of the lamp 8, and the outer or threaded terminal of the lamp is connected as through a reflector 9 with conductor 10, which may be in the form of a flat strip secured to the fiber 75 casing by rivets 11 and 12, as shown in Figs. 1 and 7. The lamp is provided with a lens 13 held in position by a flanged threaded collar 14, which engages with a threaded ring 15 mounted on the front end of tube 1. 80 Preferably the periphery of reflector 9 is insulated from collar 14 and ring 15 to prevent inadvertent lighting of the lamp when the hand lamp is laid down on a metal surface. 85

The contact mechanism by which the flow of battery current to the lamp is controlled comprises a yielding contact finger 16 stamped from the front conductive strip 10 and bent outward as shown in Fig. 3, 90 so that it protrudes into a longitudinal slot 17 cut in the fiber of the battery case 1. This yielding finger 16 serves as one of the contact elements of the switch. Enclosing the slot 17 and rivets 11 and 12, is an 95 escutcheon plate 18 of the form best shown in Fig. 2. This plate has a central longitudinal opening corresponding approximately with slot 17, and around this opening the metal of the plate is offset, as shown 100 in Figs. 2 and 6, to form a longitudinal guideway. Mounted to slide in this guideway is a housing 19 having side flanges 20 and 21 (Fig. 6) engaging beneath the inner edges of the escutcheon plate to hold the 105 housing in position while permitting it to slide longitudinally of the battery case. Attached to this housing, as by a rivet 22,

is a leaf-spring 23. The other end of the spring is bent or curved at 24 so that it may serve as a contact element opposed to the yielding finger 16. A push button 25 is carried by housing 19 and is normally held therein against an encircling flange 26 by the outward thrust of the free end of spring 23 on which the push button bears. The extreme lower or free end of spring 23 is 10 adapted to overrun the lower end of slot 17 to the position shown in Fig. 3, for in this position pressure on the push button will be ineffective to close the battery circuit to finger 16 because the free end of spring 23 15 strikes against the fiber of case 1 and cannot enter slot 17 far enough to bridge the gap between the opposing contact elements.

To impede free sliding movement of the housing along the case, the escutcheon plate 20 has pressed therein two round recesses 27 and 28 for engagement with a rounded projection 29 formed in the lower end of housing 19. Thus in Fig. 3 the push button and its associated parts are prevented from inadvertent sliding movement upward along 25 the case by the interengagement of projection 29 in recess 28.

With the switch in this position the hand lamp can be carried about in the user's 30 pocket or with a kit of tools with no danger that accidental inward pressure on button 25 will close the circuit and light the lamp, and also with little danger that the switch will accidentally slide from this position to 35 one where accidental lighting would be possible.

But when the hand lamp is to be used, the 40 push button and its housing and attached spring can be forcibly slid longitudinally of the case into the position shown in Fig. 4. In this position thumb pressure on button 25 will swing spring 19 into engagement with finger 16 and flash the lamp. With this setting of the switch, the projection 29 on 45 the housing lies in the recess 27 of the escutcheon. But if continuous burning of the lamp is desired, the push button and its associated parts can be slid still further forward into the position shown in Fig. 5, 50 where the rounded face 24 of the leaf-spring engages finger 16, even without depression of the push button. With this setting of the switch, projection 29 lies in the end of the escutcheon slot and so tends to prevent accidental opening of the circuit.

In the embodiment illustrated, the escutcheon 18 is connected permanently to one terminal of the battery as by a metal strip 55 attached to it by a rivet 31 (Fig. 2), the lower end of this strip 30 being bent outward and tucked under an inwardly projecting flange of collar 2, thereby making connection through bottom cap 3 and spring 4 with the lower or zinc terminal of battery 5.

It will be understood that the details of

the hand lamp may vary in many ways and that the switch mechanism itself is capable of other embodiments without departing from the spirit of the invention as defined by the appended claims.

70

I claim:

1. In a battery hand lamp, the combination of a battery case, a housing mounted to slide longitudinally thereof, a leaf-spring serviceable as a switch contact and having one end fastened to said housing, and a push button engaging the other end of said spring, said push button being movable along said case with said spring and housing.

2. In a battery hand lamp, the combination of a battery case, a housing mounted to slide longitudinally thereof, a push button mounted in said housing and moving therewith, and a leaf-spring having one of its ends rigidly attached to said housing and its other end engaging said push button, said spring being bent to serve as a switch contact, substantially as described.

3. In a battery hand lamp, the combination of a battery case, a housing mounted to slide longitudinally thereof, a push button mounted in said housing and moving therewith, and a leaf-spring having one of its ends rigidly attached to said housing and its other end engaging said push button and retaining said push button in said housing, substantially as described.

4. In a battery hand lamp, the combination of a battery case, a housing mounted to slide longitudinally thereof, a push button mounted in said housing and moving therewith, and a leaf-spring having one of its ends rigidly attached to said housing and its other end engaging said push button and retaining said push button in said housing, 100 said spring being bent to serve as a switch contact, and means impeding free sliding movement of said housing and said spring and push button along said case.

5. In a battery hand lamp, the combination of an insulating battery case having a longitudinal slot, a conductor secured to said case and having a finger at said slot to serve as a switch contact, an escutcheon enclosing said slot and shaped to form a guideway, a 115 housing mounted to slide in said guideway and longitudinally of said case, a leaf-spring having one end fastened to said housing, and a push button engaging the other end of said spring, said spring being bent to serve 120 as a switch contact, substantially as described.

6. In a battery hand lamp, the combination of an insulating battery case, a conductor secured to said case to serve as a switch contact, an escutcheon shaped to form a guideway, a housing mounted to slide in said guideway longitudinally of said case, a leaf-spring having one end fastened to said housing and a push button engaging the other 130

end of said spring, said spring being bent to serve as a switch contact, substantially as described.

7. In a battery hand lamp, the combination of a battery case having a longitudinal slot, a conductor secured to said case and protruding at said slot to serve as a switch contact, an escutcheon enclosing said slot and shaped to form a guideway, a housing 10 mounted to slide in said guideway longitudinally of said case, a leaf-spring having one end fastened to said housing and a push button engaging the other end of said spring, and by which said spring may be brought 15 into engagement with said finger to close the circuit, substantially as described.

8. In a battery hand lamp, the combination of an insulating battery case having a longitudinal slot, a conductor secured to 20 said case and having a finger protruding at said slot to serve as a switch contact, an escutcheon enclosing said slot and shaped to form a guideway, a housing mounted to slide in said guideway longitudinally of 25 said case, a leaf-spring having one end fastened to said housing, a push button engaging the other end of said spring and held in said housing thereby, said spring be-

ing bent to serve as a switch contact and being adapted at its free end to overrun 30 the adjacent end of the slot in the battery case to protect the switch from inadvertent closing, substantially as described.

9. In a battery hand lamp, the combination of an insulating battery case having a 35 longitudinal slot, a conductor riveted to said case and having a resilient integral finger protruding at said slot to serve as a switch contact, an escutcheon enclosing said slot and rivets and shaped to form a guideway, 40 a housing having side flanges engaged by said escutcheon, said housing being mounted to slide in said guideways longitudinally of said case, a leaf-spring having one end fastened to said housing, a push button engaging the other end of said spring and held 45 in said housing thereby, said spring being bent to serve as a switch contact and being adapted at its free end to overrun the adjacent end of the slot in the battery case and 50 thereby protect the switch from inadvertent closing, and means impeding free sliding movement of said housing and spring along said case, substantially as described.

In testimony whereof I affix my signature. 55
ARTHUR P. PAINE.
